US0D1046212S

(12) **United States Design Patent** (10) Patent No.: **US D1,046,212 S**
(45) Date of Patent: ** Oct. 8, 2024

(54) **GROW LIGHT**

(71) Applicant: **Shenzhen Westland technology Co., Ltd.**, Shenzhen (CN)

(72) Inventors: **Taijun Ye**, Shenzhen (CN); **Dequan Lin**, Shenzhen (CN); **Wuyi Li**, Shenzhen (CN); **Jianjun Huang**, Shenzhen (CN)

(73) Assignee: **Shenzhen Westland technology Co., Ltd.**

(**) Term: **15 Years**

(21) Appl. No.: **29/826,507**

(22) Filed: **Feb. 14, 2022**

(51) LOC (14) Cl. **26-05**

(52) U.S. Cl. USPC **D26/24**

(57) **CLAIM**

The ornamental design for a grow light, as shown and described.

DESCRIPTION

FIG. 1 is a first perspective view of a grow light showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the grow light and form no part of the claimed design.

1 Claim, 8 Drawing Sheets
